UNITED STATES PATENT OFFICE.

SAMUEL N. SILVER, OF AUBURN, MAINE, ASSIGNOR TO HIMSELF AND
LUCIUS S. CHANDLER, OF SAME PLACE.

STEAM-ENGINE.

SPECIFICATION forming part of Letters Patent No. 225,651, dated March 16, 1880.
Application filed August 1, 1879.

To all whom it may concern:

Be it known that I, SAMUEL N. SILVER, of Auburn, in the county of Androscoggin and State of Maine, have invented a new and Improved Steam-Engine, of which the following is a specification.

In the accompanying drawings, Figure 1 is a sectional plan view of my improved machine. Fig. 2 is a vertical longitudinal section on line $x-x$ of Fig. 1. Fig. 3 is a sectional plan view on line $y-y$ of Fig. 2. Fig. 4 is a cross-section of the cylinder. Fig. 5 is an end view of the port-chamber.

Similar letters of reference indicate corresponding parts.

My improvements relate to engines and pumps adapted for use with steam or water, and as stationary, marine, or locomotive engines, or as steam fire-engines; and the object is to attain an engine of simple and durable construction adapted for running at high speed.

I make use of a compound cylinder containing numerous chambers fitted with pistons, that are connected by ball-joints with a toothed wheel that is fitted to revolve in a plane more or less inclined to the axis of the cylinder. The cylinder is fitted to and connects with a port-chamber, whereby the pistons are subjected to the pressure, and the movement thus given to the toothed wheel is imparted to the cylinder by an intermediate gear, so that a continuous rotary motion is obtained.

I also make use of regulating devices for governing the speed, all of which features will be described more particularly with reference to the accompanying drawings.

A is a bed-plate, upon which, in suitable bearings, the parts of the apparatus are supported. B is the compound cylinder on a shaft, a , that is fitted to revolve freely in fixed bearings. C is the port-chamber, fixed on bed A, through the center of which shaft a passes, and against the open side of which cylinder B is fitted with a rabbeted joint, that is rendered steam or water tight by an annular packing of rubber or metal. The chamber C is divided, by a solid partition, a' , into two passages, (see Figs. 2 and 5,) opening against the end of cylinder B, and connected one with the inlet-opening b and the other with the outlet or exhaust c .

The cylinder B is formed with numerous chambers, d , that are arranged in a circle concentric with shaft a and equidistant from each other. Within each chamber d is a piston-head or plunger, e , formed with a groove for leather or metallic packing, and connected by a rod, f , with a wheel or disk, g , that is fitted to a shaft, h .

The connection of the rods f to g is made by ball-joints, and the boxes i of shaft h are supported on a post, k , from a plate, l , that is hung, by a pivot, l' , on bed A, thus forming a swing-stand, whereby the shaft h may be moved in a horizontal plane to vary its inclination to shaft a .

The shaft h is moved and held by cross-shaft m , having a threaded portion that engages with a nut pivoted on the under side of box i , the outer end of which shaft carries a gear-wheel, n , that is moved by the regulating mechanism, as hereinafter described.

The disk g is formed with radial cogs, which engage the projecting teeth of a ring or disk, o , which is intermediate of the disk g and cylinder B, and connected with the latter.

In operation as a motor the steam or water supplied under pressure by the inlet b exerts its force upon the heads e of the chambers d , that are open to the passage above the partition a' of port-chamber C. The chambers d , below the partition a' are open to the exhaust c , while one intermediate chamber at each side is covered by the partition a' . The power, speed, and length of stroke are dependent on the inclination of the wheel g to the axis of cylinder B, and the pivot l' , on which the wheel g and shaft h swing, being placed directly under the ball-joint of rods f , next to inlet b , each piston commences to move outward by the pressure at that side and continues the movement until the opposite side is reached, when the chamber passes behind the partition a' to the exhaust. By this action a continuous rotary motion is given to wheel g , and the pressure is exerted in all the chambers of the cylinder above the partition a' , the cylinder B and shaft a being turned by wheel g .

The automatic regulation of the speed is effected by the devices next described.

At the side of frame A, in suitable bearings, is a shaft, p , driven by a belt from a pulley, q , on shaft a . r is a wheel fast on shaft p , and

fitted with centrifugal balls r' , that are on the ends of arms s , which connect by ball-joints with a collar, s' , on shaft p . Spiral springs fitted on the supporting-rods of balls r' oppose the centrifugal action. $t t$ are small bevel-gears loose on shaft p , and meshing with the bevel-gear n at opposite sides of its shaft m . These gears t are formed with conical hubs that enter the flaring ends of the sleeve u , which turns with shaft p , but is capable of endwise movement to clutch either gear t . A flanged collar behind each gear t serves to retain the gear in place. u' is a rod, fitted to slide in fixed bearings, having a forked arm, t' , that enters an annular groove in sleeve u , and a second forked arm, p' , that enters an annular groove in the collar s' , whereby the sleeve u , rod u' , and collar s' are moved together by the action of the centrifugal balls. The connection of the forked arm p' with rod u' is made by a hub, from which p' projects and into which the rod u' enters. A thumb-screw, v , permits adjustment of this connection for regulating the position of the sleeve u with reference to the gears $t t$. These parts being set for the desired speed, when that speed is exceeded the outward movement of the balls causes the sleeve u to clutch one gear, t , thereby turning gear n and screw-shaft m in the direction for lessening the inclination of shaft h , which action shortens the stroke of the pistons and reduces the purchase on wheel g , thus reducing the speed. A reduction of speed below the normal point produces a reverse action and effect.

The pivoted plate l , on which the swinging stand of shaft h is supported, is connected by a rod, w , with a yoke, w' , that is fitted to slide on screw-rods d' beneath bed A . Around rods d' are spiral springs, acting between nuts c' and yoke w' so as to exert a spring-tension on

plate l , which equalizes the swinging motion of plate l and its attached parts. The tension of the springs is regulated by turning the rods d' , thereby moving the nuts c' to compress or release the springs. 45

The above construction furnishes a motor adapted for high speed and durable in all its parts. The cylinder B , shaft h , and its attached parts will be covered by a protecting- 50 case, as shown.

The machine may be built of any size according to the power required, and with small machines the regulator is not required.

Having thus fully described my invention, 55 I claim as new and desire to secure by Letters Patent—

1. In a motor or pump, the combination of the revolving cylinder B , formed with chambers d , the fixed port-chamber C , having inlet 60 and outlet passages, divided by a solid partition, the toothed wheel or disk o , connected to cylinder B , the gear-wheel g , meshing with o and fitted to revolve in a plane inclined thereto, and the heads or plungers e , working in the 65 chambers of cylinder B and having their rods connected by loose joints with wheel g , substantially as herein shown and described.

2. In a motor or pump, the combination, with the wheel g and its shaft h , of the boxes 70 i , post k , pivoted plate l , screw-shaft m , and nut, substantially as and for the purposes set forth.

3. In combination with the plate l and swing-stand of shaft h , the rod w , yoke w' , screw- 75 rods d' , nuts c' , and spiral springs, substantially as and for the purposes specified.

SAMUEL N. SILVER.
